UNITED STATES PATENT OFFICE.

EDWIN J. AKINS, OF MOUNDSVILLE, WEST VIRGINIA.

ROAD-GRADING MACHINE.

1,103,242.

Specification of Letters Patent. Patented July 14, 1914.

Application filed October 10, 1911. Serial No. 653,896.

To all whom it may concern:

Be it known that I, EDWIN J. AKINS, a citizen of the United States of America, and resident of Moundsville, county of Marshall, 5 and State of West Virginia, have invented certain new and useful Improvements in Road-Grading Machines, of which the following is a specification.

This invention relates broadly to road 10 building machines, and specifically to a road grader and scraper.

The primary object of the invention is to provide a self-propelled, or traction, vehicle embodying a road building machine adapted 15 to reduce the ground to an even grade as it advances thereover.

A further object is to provide a machine of the character mentioned whereby low mounds, banks, or ridges of earth are dug 20 up as it advances, and whereby the loosened dirt is removed or shifted aside for forming a regular roadway of substantially even grade, the machine itself advancing over the newly made roadway.

With these and other objects in view, all 25 of which will hereinafter be made apparent, the invention resides in the features of construction, arrangement of parts and combinations of elements which will hereinafter 30 be fully described, reference being had to the accompanying drawings, forming a part of this specification, in which—

Figure 1 is a top plan view of my invention; Fig. 2 is a side elevation of the same; 35 Fig. 3 is a horizontal section of the same; and Fig. 4 is a vertical section on the line 4—4, Fig. 1.

Referring to said drawings in which like designating characters distinguish like parts 40 throughout the several views 1 1 indicate opposite side portions of the frame of a movable carriage or self-propelled vehicle which may be of any appropriate character, but which is preferably of that type common 45 in traction engines. Journaled in suitable bearings 2 provided at the ends of said side portions 1 of the frame is a transversely disposed shaft 3 which is driven by any suitable type of gearing, the gearing arrangement herein shown being but one of 50 various kinds which might be employed, and comprising a suitably driven drive-shaft 4 having a pinion 5 in mesh with a gear wheel 6 mounted on a shaft 7 located 55 on the frame parallel to and at a spaced distance from said shaft 3. Motion is com-

municated from the shaft 7 to the shaft 3 through intermeshing gears 8 and 9 respectively carried by said shafts. Rotatable on said shaft 3 outside the frame are traction wheels 10 to which motion is communicated in any appropriate manner, as by pinions 11 carried by the shaft 7 in engagement with internal gears 12 carried by, or forming part of, said wheels.

Fixed on the opposite ends of the shaft 3 are sprocket wheels 13 connected by sprocket chains 14 to sprocket wheels 15 fixed upon a shaft 16 located in front of and parallel to said shaft 3 and journaled in the front 70 ends of longitudinally directed brace-arms or bars 17 having their rear ends loosely mounted on the ends of shaft 3, rotation of said shaft 16 being thus communicated from said shaft 3.

Fixed upon the shaft 16 is a plurality of spaced radial arms 18 upon which is rigidly mounted, as by bolts 19, a helical blade 20 which is adapted to propel laterally dirt, or loosened earth, with which it comes in engagement. For digging up, or loosening, banks or mounds of earth as the carriage advances, suitable plowshares or shovels 21 are rigidly mounted upon the outer ends of the arms 18 to project beyond the peripheral edge of the helical blade 20. Rotation of the shaft 16 thus causes the shovels 21 to enter and break up ground elevated above the plane of the roadway over which the machine travels, and the revolving blade, 90 operating against the breast of earth, engages and moves the loosened dirt laterally to an out of the way position.

In operation, the carriage is moved forward at a low rate of speed, regulated according to the character of the earth acted upon. As is obvious, a change-speed gear of appropriate type may be employed whereby the speed of the carriage may be increased or decreased at will without producing a corresponding change of speed of the earth digging and shifting mechanism. Suitable means is provided for elevating and lowering the shaft 16 as may be desired, the means herein shown comprising inclined 100 supporting arms 23 having their front ends loosely mounted in supporting relation to said shaft and having their rear ends pivotally connected to the upper ends of substantially upright supports 24 in the lower 110 ends of which the shaft 3 is rotatable. Rods, cables, or chains 25 connected to the upper ends

of said supports 24 are extended rearwardly whereby tension may be placed upon said supports for inclining the latter rearward and to thus elevate the digging and shifting mechanism. As is obvious, the parts constituting the present invention may be mounted to travel forward with the movement of the vehicle by which they are carried; or, said parts may be mounted upon a carriage which is movable independent of the movement of said vehicle.

Having thus described my invention, what I claim as new, and desire to secure by Letters Patent, is—

- 15 1. In a road building machine, the combination with a movable carriage, of a shaft journaled on the carriage frame and lying transversely of the direction of movement of the carriage, gearing for said shaft, a second shaft located in front of and parallel to the first-named shaft, substantially horizontal brace-arms having their opposite ends loosely connected to said shafts whereby the second shaft is maintained at a fixed 20 distance in front of the first shaft, gearing interposed between said shafts, radially extending arms having a spiral disposition on said second shaft, earth-loosening shovels carried by said radial arms, and a helical 25 blade mounted in fixed relation to said second shaft and of which said shaft forms the axis whereby loosened earth is moved laterally from the path of the advancing carriage to afford a solid and smooth roadway 30 over which the wheels of the latter advance.
- 35 2. In a road grader, a traction vehicle, a shaft journaled in front of said vehicle,

gearing interposed between the vehicle and said shaft whereby traction movement of the former effects rotation of the latter, means 40 for bracing said shaft with respect to said vehicle, radial spirally disposed arms mounted on said shaft, digging instruments mounted upon the outer ends of said arms, and a continuous blade disposed spirally 45 about said shaft and rigidly supported by said arms whereby earth loosened by said instruments is shifted laterally in a horizontal direction out of the path of the advancing vehicle to form a smooth and solid 50 roadway for the wheels of the latter.

3. In a road grader, a traction vehicle, a shaft journaled in front of said vehicle, gearing interposed between the vehicle and said shaft whereby traction movement of the former effects rotation of the latter, means 55 for bracing said shaft with respect to said vehicle, radial spirally disposed arms mounted on said shaft, digging instruments mounted upon the outer ends of said arms, a blade disposed spirally about said shaft and rigidly sustained by said arms, whereby earth loosened by said instruments is shifted horizontally in a direction transverse to the line of travel of the vehicle to 60 form a solid and smooth roadway for the wheels of the latter, and means for elevating and lowering said shaft.

In testimony whereof I affix my signature in presence of two subscribing witnesses.

EDWIN J. AKINS.
